UNITED STATES PATENT OFFICE.

ROBERT F. PATTERSON, OF CLINTON, MASSACHUSETTS, ASSIGNOR TO THE
BIGELOW CARPET COMPANY, OF SAME PLACE.

MOQUETTE CARPET.

SPECIFICATION forming part of Letters Patent No. 432,763, dated July 22, 1890.

Application filed February 27, 1888. Serial No. 265,363. (Specimens.)

To all whom it may concern:

Be it known that I, ROBERT F. PATTERSON, of Clinton, county of Worcester, State of Massachusetts, have invented an Improvement in 5 Moquette Carpets, of which the following description, in connection with the accompanying drawings, is a specification, like letters on the drawings representing like parts.

This invention relates to that class of carpet known as "Moquette," it being a carpet wherein rows of tufts are confined in place by weft-threads.

My invention has for its object to improve that class of Moquette carpet where the weft-thread employed is inserted double and is of the same size, there being but one weft, it serving not only to enter and lock with the warps to form the body of the fabric, but also to hold the tufts constituting the face of the 20 fabric.

In my experiments to improve Moquette carpets I have discovered that difficulties and objections inherent in such carpets as previously made may be overcome by a change in 25 the structure of the fabric. The fabric herein shown may be made on a loom such as described in United States Patent No. 330,069, dated November 10, 1885, with but a slight difference in the order of opening the sheds 30 in the body-warps.

In accordance with my invention the sheds in the body-warps remain open for the reception of three shots or crossings of filling inserted double, one of the three shots of filling 35 receiving the tufts about it, the other two shots being beaten into the shed, one close to and against the side of the tuft to aid in holding it in place, while the other is beaten below the bight of the tuft on the weft about which 40 it is looped, keeping said tuft set up closely about the weft which it encircles.

In the simpler form of my invention I employ two sets of harness-frames to work the warp-threads in pairs, the two threads of each 45 pair appearing side by side at one and then at the other face of the carpet, one thread being at one side and the other thread at the other side of the tuft, the same pair of threads co-operating with the same longitudinal row of 50 tufts; but, if desired, I may use a third har-

ness for a stuffer-warp, so as to give a little more body to the carpet, such stuffer-warp being laid in straight.

Figure 1 in longitudinal section shows my improved fabric with the threads widely separated. Fig. 2 is a similar view of a modification with the stuffer-warp omitted. Fig. 3 is a plan view showing some of the warps with the crossing-weft and omitting the stuffer-warp; and Fig. 4 is a section showing the carpet, represented in Figs. 2 and 3, as beat up closer.

The warp-threads *a* and *b* are carried by two harness-frames and arranged in pairs, and they are so opened or shed as to remain open 65 for three picks after each crossing of the warp to form a shed, each shed in the main warps *a* and *b* thus receiving three shots of weft or filling *d d' d''*, as shown, the shot *d* receiving upon it the tufts *e*, while the shots *d' d''*, when 70 beat into the shed, occupy the position shown in Fig. 4 with relation to the shot of filling *d* holding the tufts, the said shots aiding in binding the tufts *e* and forming a seat for the tufts on the shot *d*, setting up said tufts, as it were, 75 thus holding the rows of tufts very firmly and very close together.

To strengthen the carpet and add body thereto I may incorporate with it a stuffer-warp, as *c*, Fig. 1, it separating the two shots 80 *d d' d''* and lying straight in the fabric.

By separating the warps to form sheds and by leaving the shed open for the reception of the three shots of filling inserted double before again crossing the shed, it is possible to 85 make a heavier and stronger fabric than by any other mode of weaving known to me, and it is also possible to get the three shots of filling beaten into the same shed, so that the shots which do not directly receive the tufts about 90 them serve thoroughly to bind and set up and compact the tufts closely together. The warp-threads are so moved that when one pair is up the other pair is down; but it is not material that all the pairs of threads *a* or of threads *b* 95 should be up simultaneously.

I am aware that it has been attempted to provide a Moquette carpet with a continuous back, as in United States Patent No. 257,395; but in the fabric described in said patent the 100

tufts surrounding one weft, as d , are not held in place therein by the contact against the said tufts of a second weft without the intervention of a warp-thread, and as a result the rows 5 of tufts are not as much set up, nor are they as close together when beat up, nor are the individual tufts as closely held.

What I claim is—

The herein-described tufted carpet, composed of two sets of body warp-threads a and b , arranged and worked in pairs, two threads a constituting a pair and two threads b constituting a pair, and the threads of each pair appearing side by side at one and then 10 at the other face of the carpet and falling on opposite sides of the longitudinal row of tufts common to such pair, and three shots of fill- 15

ing in each shed between the body warp-threads, one shot, as d , receiving about it the tufts e , while another of the said three shots 20 of filling, as d' , comes in direct contact with the said tufts on the shot d without the intervention of a warp between them, the other shot d' being beaten into position under the shot d , about which the said tufts are looped, 25 to thus constitute a seat for the said tufts and set them up, substantially as described.

In testimony whereof I have signed my name to this specification in the presence of two subscribing witnesses.

ROBERT F. PATTERSON.
